UNITED STATES PATENT OFFICE.

LOUIS JAMES FULLER, OF BROOKLYN, NEW YORK, ASSIGNOR TO DUPARQUET, HUOT & MONEUSE COMPANY, OF NEW YORK, N. Y., A CORPORATION OF NEW YORK.

HEATING ELEMENT.

Application filed February 2, 1922. Serial No. 533,577.

To all whom it may concern:

Be it known that I, LOUIS JAMES FULLER, a citizen of the United States, residing at Brooklyn, in the county of Kings, State of New York, have invented certain new and useful Improvements in Heating Elements; and I do hereby declare the following to be a full, clear, and exact description of the invention, such as will enable others skilled in the art to which it appertains to make and use the same.

My invention is an improvement in electric heating elements, and relates particularly to elements of the type designed to be submerged in a liquid to be heated. Heating elements of this type are very susceptible to overheating, and consequent injury, when for any reason the liquid falls to a point such that the heating or resistance coils of the element are no longer submerged. In order that the heating element may function properly, the coils of the resistance wire must be thoroughly insulated from each other, and to insure complete and permanent insulation, the wire is usually embedded in cement. The heating element is rapidly cooled through convection, the surrounding liquid carrying away the heat, and there is no danger of overheating, so long as the element is submerged. When, however, for any reason, as for instance neglect of the attendant, the liquid falls below the top of the element, so that a portion thereof is exposed to the air, the element rapidly overheats, because the heat is no longer carried away, and injury results, the heating wire fusing at some point in the exposed portion, and breaking the circuit. The wire is usually in coils, and so arranged in the element, that portions of a number of coils will simultaneously emerge when the liquid falls below the top of the heater. It is in these portions that the break occurs and it is impossible to exactly, or even approximately, locate the injury. The entire element must be removed, and afterwards dismantled, to locate the injury, a procedure that requires time, and which is expensive. In addition the vessel, as for instance a coffee urn, is out of commission for an extended period.

In the present invention, I segregate an independently insulated portion of the heating or resistance wire, and arrange it in such relation with respect to the remainder, that

such auxiliary portion will first emerge when the liquid falls below the safety level, and I connect the said portion with the remainder, in such manner that it may be easily detached and removed, to be replaced by another, thereby to permit the heater to function with as little loss of time as possible.

In the drawings:

Figure 1 is a vertical section of a coffee urn, provided with the improved heating element,

Figure 2 is a section on the line 2—2 of Figure 3,

Figure 3 is a bottom plan view of the heating element,

Figure 4 is a diagrammatic view of the wiring,

Figure 5 is a perspective view of one of the insulating tubes or casings.

In the present embodiment of the invention, the improved heating element or unit, comprises an annular cup-shaped casing 1, having at its bottom a transverse web 2, which has a central threaded perforation 3, axial to the casing 1. The web 2 is at the open end of the casing, and the casing has at the said end an external annular flange 4, which is adapted to fit against the wall 5 of the vessel 6, within which the element is arranged, the said vessel 6 being in the present instance, a coffee urn, having the usual liquid gauge 7, and safety valve 8.

The heating or resistance wire indicated at 9, is wound into a plurality of coils, and the individual coils are arranged within the cylindrical bores of insulating tubes 10. These tubes are placed within the casing 1, in the manner shown in Figure 3, there being a plurality of pairs of tubes, the members of the pair lying radial to the casing. The coils are so arranged in the tubes, that the wire is continuous from a binding post 11 to which one terminal of the wire is connected, to a binding post 12 to which the other terminal of the wire is connected. Referring to Figure 3, it will be seen that the wire passes from the terminal 11 through the adjacent tube 10, across at the opposite end to the succeeding tube in the outermost series, through said tube in the opposite direction, and across to the succeeding tube of the series. This procedure is continued about the tubes of the outermost series, until

the wire from the last tube of the said series is passed over to the adjacent tube of the innermost series, and the wire passes back in the opposite direction to connect with the terminal 12. Thus, all of the coils in the tubes 10 are arranged in series, the current flowing from the terminal 11, through all of the coils, to the terminal 12. Cement indicated at 13 is arranged within 10 the casing, the said cement filling the space between the ends of the tubes and the closed end of the casing, filling the space between the tubes, and filling the space within the tubes about the coils. The cement also makes 15 a plug 14 which closes the open end of the casing, and through which the terminals 11 and 12 extend.

In making a heater of known capacity, as for instance 2 k. w., I will make the coils in 20 the tubes 10 of a capacity of 1950 watts. The remaining 50 watts capacity, I would provide for by an auxiliary coil 16, which is disposed at a higher level than the main portion 25 of the heating element, and which is segregated therefrom, and independently insulated. In the present instance, I arrange this auxiliary coil within a casing 17 of the same material as the casing 1, one end of the auxiliary casing being closed, and the 30 other end open, and at the said open end, I provide a threaded portion 18 for engaging the threaded opening 3 of the casing 1. The casing 17 has a hexagonal flange 19, for convenience in turning the same, and within 35 the casing, and arranged axially thereof there is a tube 20 of insulating material, as for instance porcelain. The wire 21 passes through this tube, and is coiled around one end of the same to form the coil 16, after 40 which the end of the wire passes out along- side the porcelain tube 20, and is connected with a binding post 22. The opposite end of the wire 21 is connected with the terminal 12 before mentioned. The space between the tube 20 and the casing 17 is filled with 45 cement, and the casing, and the tube 20, are of such length, that when the casing is screwed into the opening 3, the coil 16 will be at a higher level, than the coils of the wire 50 9. The casing 1 is arranged within the vessel 6, extending through an opening in the bottom thereof, with the flange 4 abutting the under face of the bottom, and it is se- 55 cured thereto in any suitable or desired manner. When so arranged, the coil 16 is at higher lever than any other portion of the wire 9, and when the liquid in the vessel falls below the safety line, the coil 16 will 60 be first to emerge from the liquid. Hence this portion of the wire will be the first to overheat the fuse. When this happens, the wire 21 is disconnected from the terminals 12 and 22, and the casing 17 is removed, to 65 be replaced by another, when the heating element is again in condition for use. The

terminals 12 and 22 are connected with the usual circuit, and the circuit is controlled by a switch indicated at 23.

The casing 17, containing the auxiliary coil 16 may be considered as a renewable cartridge which serves to protect the main part of the heating element and which may readily be replaced without injuring or in any way disturbing the main portion of the element. 75

I claim:

1. A heating element comprising a main portion consisting of a plurality of coils of resistance wire and an auxiliary portion comprising a single coil of resistance wire, 80 said coil being segregated and independently insulated and arranged at a different level from the coils of the main portion of the heating element, whereby said coil may serve 85 to prevent the resistance wire in the main portion of the unit from overheating.

2. A heating element comprising a main portion consisting of a plurality of coils of resistance wire and an auxiliary portion comprising a single coil of resistance wire, 90 said coil being segregated and independently insulated and arranged at a higher level from the coils of the main portion of the heating element, whereby said coil may serve 95 to prevent the resistance wire in the main portion of the unit from overheating.

3. A heating element comprising a main portion consisting of a plurality of coils of resistance wire connected in series and insulated from each other, and an auxiliary coil arranged at a higher level than the coils in said main portion of the heating element, and means for disconnecting said auxiliary coil from the remaining coils. 100

4. A heating element comprising a resistance wire arranged in coils, one of said coils being segregated, a casing for said coil and a casing for the other coils with which said first named casing is detachably connected. 105

5. A heating element comprising a resistance wire arranged in coils, one of said coils being segregated, a casing for said coil, and a casing for the other coils with which said first named casing is detachably connected, 110 said last named casing being of a length to project said coil beyond the other coils for the purpose specified.

6. A heating element of the character specified, comprising an annular casing open 120 at one end, a plurality of series connected heating coils within the casing insulated from each other and from the casing, an independently insulated coil in series with the other coils, and means for supporting said last named coil at a different level from the other coils whereby said last-named coil may serve to prevent the remaining coils 125 from overheating, said last-named coil being adjustably connected to the remaining coils. 130

7. A heating element of the character

- specified, comprising an annular casing open at one end, a plurality of series connected heating coils within the casing insulated from each other and from the casing, an independently insulated coil in series with the other coils, and means for detachably connecting said last named coil to the casing to support said coil at a different level from the other coils.
8. A heating element of the character specified, comprising an annular casing open at one end, and having a transverse web at the said end provided with a central opening, a plurality of series connected heating coils within the casing insulated from each other and from the casing, a casing detachably connected with the web and extending through the opening, and a coil of resistance wire in the said casing in series with the other coils, said casing being of a length to extend the coil beyond the other coils.
9. In a heating element of the character specified, an annular casing open at one end, a plurality of insulating tubes within the casing, each tube carrying a heating coil, said coils being connected in series, each of the tubes having an external rectangular cross-section, and being cored to receive the coil.
- In testimony whereof I affix my signature.

LOUIS JAMES FULLER.
